RESERVE HOPPER FOR ACETYLENE-GAS GENERATORS.

Application filed April 14, 1925. Serial No. 23,161.

Our invention relates to improvements in acetylene gas generators, more particularly to a reserve carbide supply hopper or container for a gas generator having a main carbide supply container and an automatic feed means for feeding the carbide from the main supply container into a liquid within the generator, and it consists in the combinations, constructions and arrangements herein described and claimed.

An object of the invention is to prevent a break in the operation of a gas generator of the character described by providing a reserve carbide supply container or hopper which will be filled at the time the main supply container is filled and which will hold a sufficient quantity of acetylene to assure continued operation of the generator for a considerable length of time after the supply of carbide in the main supply container has been exhausted.

A further object of the invention is the provision of an auxiliary or reserve supply container in association with the main supply container, the reserve supply container affording facilities permitting of the discharge of a part of the contents thereof directly into the liquid within the generator to render the means for actuating the automatic feed means of the main supply container effective, the remainder of the contents of the reserve supply container being discharged into the main supply container and thence as required into the liquid in the generator.

Other objects and advantages of the invention will be apparent from the following description, considered in conjunction with the accompanying drawings, in which:

Figure 1 is a view mainly in side elevation, showing a carbide gas generator equipped with a reserve carbide supply container embodying the invention, portions of the shell of the generator and of the main supply container being broken away to disclose the reserve supply container, and other parts of the shell of the container and of the main supply container being shown in section;

Figure 2 is a transverse vertical section through the reserve supply container, showing in elevation the feed or dump valve at the lower end thereof together with parts of the valve operating mechanism;

Figure 3 is a fragmentary longitudinal vertical section through the reserve supply container and the associated portion of the

main supply container, showing the dump valve of the reserve supply container fully closed;

Figure 4 is a view similar to Figure 3, showing the dump valve of the reserve supply container in the position which it occupies when it has been moved approximately half way from fully closed to fully open position;

Figure 5 is a view similar to Figures 3 and 4, showing the reserve supply dump valve in fully open position; and

Figure 6 is a horizontal section taken along the line 6—6 of Figure 3.

In carrying out the invention we make use of an acetylene gas generator having an outer shell 1, the lower portion of which is formed to provide a tank designated 2 which is adapted to hold water or other liquid substantially to the level indicated at 3 in Figure 1 or to any lower level. A main carbide supply container is supported within the shell 1 above the level of the liquid within the tank 2. This main carbide supply container may comprise a vertically disposed hollow body 4 which is closed at its upper end by a lid 5 and is provided at its lower end with a bottom member 6 having substantially the shape of an inverted frustum of a cone. The bottom member 6 constitutes a hopper having a feed or main discharge opening 7 at its lower end with which a dump valve 8 is associated, the action of the dump valve being automatic and resulting in the feeding of a certain quantity of carbide from the main container into the liquid in the tank 2 whenever the supply of gas within the generator reaches a definite low level. Any suitable known means operable in response to fall of pressure of gas within the generator to actuate the valve 8 to feed carbide into the liquid in the tank may be employed since the particular construction for controlling the feeding of carbide from the main supply container into the liquid forms no part of the present invention.

The lid 5 of the main carbide supply container has a filler opening 9 which is located at one side of the vertical central line of the main supply container, this filler opening normally being closed by a cap 10 or other like closure.

The bottom member 6 or hopper of the main supply container is provided with a secondary discharge opening 11 which is

located adjacent to the juncture of the bottom member 6 with the body 4 of the main supply container. A reserve carbide supply container comprises a vertically disposed hollow body which is located within the main supply container directly above the opening 11 and underneath at least a portion of the filler opening 9, this body being secured to the adjacent wall of the main supply container by rivets 13 or like fastening devices so that the opening 11 is located at a level not lower than that of the lowest portion of the body of the reserve supply container and the latter therefore tends to prevent flow of carbide from the main supply container through the opening 11. The hollow reserve supply body is open at both its upper and lower ends and preferably is formed to be substantially rectangular in cross sectional contour, having parallel vertical side walls 12^a and parallel vertical end walls 12^b, and 12^c, respectively, the latter being attached by the rivets 13 to a vertical wall of the main supply container, as hereinbefore pointed out. A baffle or deflector within the reserve supply container comprises a plate having a width approximately equal to the distance between the side walls 12^a of the reserve supply container, this plate being bent to provide an inclined upper portion 14 which has an attaching portion 15 at its upper end secured by rivets 16 to the end wall 12^c and a horizontal brace portion 17 which extends from the lower end of the inclined portion 14 to the end wall 12^c and is merged into an attaching portion 18 which is secured to the end 12^c by rivets 19. The baffle or deflector member just described is located well toward the lower end of the reserve supply container. A passage indicated at 20 thus is produced between the lower end of the inclined baffle 14, the vertical end wall 12^b, and portions of the side walls 12^a, this passage of course being of less area than the cross sectional area of the reserve supply container. A valve for controlling the passage of carbide from the reserve supply container is in the form of a plate which has a width slightly less than the distance between the side walls 12^a and which comprises a flat outer end portion 21, and a flat inner end portion 22 which is joined integrally to the outer end portion 21 by an enlarged portion 23 which extends transversely of the plate. The portions 21 and 22 extend at an obtuse angle to each other and the enlarged portion 23 is formed with a bore extending transversely of the plate for the reception of a horizontal pivot element 24 which extends transversely of the reserve supply container below the passage 20.

With this arrangement, the valve will be supported within the lower part of the reserve supply container to rock about a horizontal axis extending transversely of the re-

serve supply container. The end portion 22 of the valve has an integral extension 25 which extends upwardly at an obtuse angle to the portion 22 for part of its length, and then is bent rearwardly for the remainder 70 of its length as indicated at 26. The portion 25 of the valve will rest flatwise against the outer end wall 12^b when the portion 21 of the valve is substantially horizontal and is in contact at its extremity with the end wall 75 12^c as shown in Figure 3 of the drawings. The valve then will constitute a bottom for the reserve supply container and will prevent granular or powdered material, such as carbide, from falling from the reserve supply container past the valve. The portion 26 of the valve is adapted to engage with the lower end of the inclined deflector when the valve has been rocked about the axis of the pivot element 24 from the position shown in Figure 3 slightly beyond the position shown in Figure 4 and to then prevent passage of carbide into the space between the valve and the horizontal bottom member 17 of the baffle structure 17-14. The lower outer corner position of the hollow body of the reserve supply container is beveled as indicated at 27 to rest flatwise against the inclined bottom member 6 of the main supply container in position to surround the opening 11, whereby carbide will be prevented from passing from the main supply container through the opening 11, as previously stated.

The element 24 which has been termed a pivot element is in fact a rock shaft to which the enlarged portion 23 of the reserve supply container feed valve is secured. This rock shaft 24 is journaled in alined openings in the side walls 12^a of the reserve supply container and has an extended end portion 100 to which a rocker arm 28 is secured. A lifter rod 29 is pivotally attached at its lower end, as at 30 to the outer end of the rocker arm 28 and extends slidably through an aperture 31 in the cover 5 of the main supply container. The lifter rod 29 has the upper end portion thereof bent laterally as indicated at 32 to engage with the cover 5 and thus to limit the downward movement of the lifter rod. The laterally turned upper end portion of the lifter rod extends beyond the rim of the cover 5. An operating member for raising the lifting rod comprises a vertical rod 33 which is disposed between the shell 1 of the generator and the body of the main supply container and is slidable vertically in vertically spaced guiding and retaining brackets 34 which are carried by the shell 1. The rod 33 is bent inwardly and upwardly at its lower end as at 35 and then extends vertically upward, as at 36 between the usual vertically movable bell 37 of the generator and the body of the main supply container and terminates at its upper end underneath the laterally turned upper end por-

tion 32 of the valve lifter rod 29. The shell 1 of the generator of course is formed so that access to the upper portion thereof may be had when desired and the upper end portion 5 of the rod 33 therefore can be grasped and manipulated when desired to cause the upper end of the vertical member 36 to engage with the laterally turned upper end portion 32 and to lift the lifter rod 29 upward, thus rocking the shaft 24. The bell 37 per se forms no part of the present invention but is an element of the hereinbefore mentioned mechanism for causing the valve 8 of the main supply container to be actuated 10 to dump a quantity of carbide into the liquid in the tank 2 when the gas supply within the generator falls to a low level, the bell 37 then moving downward in the shell 1 until the head thereof contacts the upper end of 15 a vertically movable valve operating rod 38 which is pivotally attached at its lower end to the valve 8. From the foregoing description of the various parts of the device, the operation thereof may be readily understood. 20 Carbide in granular or any other suitable form is dropped through the filler opening 9 into the main supply container and since the filler opening 9 is above the open upper end of the reserve supply container, the latter 25 also will be filled when the main supply container has been filled to a level above that of the upper end of the reserve supply container body, as shown in Figure 1. At this time, the feed or dump valve of the reserve 30 supply container will be closed as illustrated in Figure 3 and will cooperate with the portions of the side walls 12^a which are located directly below the horizontal wall 17 of the obstruction 17-14 to separate a given quantity 35 of carbide from the remainder of the supply of carbide within the reserve supply container. The carbide within the main supply container is fed by means of the valve 8 and its operating mechanism into the liquid 40 within the tank 2 as required to prevent lowering of gas supply within the container below a definite amount until the supply of carbide in the main supply container is exhausted. The rod 33 then may be grasped 45 and manipulated to swing the reserve supply feed valve from the position shown in Figure 3 through the position shown in Figure 4 to the position shown in Figure 5. It will be observed that the upper end portion 26 of 50 the reserve supply feed valve contacts with the lower end of the inclined deflector 14 before the opposite end portion of the valve has been swung downwardly to the level of the upper end of the discharge opening 11 and therefore communication between the space within the reserve supply container above the inclined deflector 14 and the space 55 within the reserve supply container below the horizontal supporting member 17 and 60 between the latter and the reserve supply feed valve is shut off before carbide is permitted to pass from the valve through the opening 11. When the reserve supply feed valve is in fully open position, as shown in Figure 5, the outer end portion thereof engages with the lower wall of the opening 11 both for the purpose of limiting the swinging movement of the reserve supply feed valve from closed position and for guiding carbide from position on the reserve supply feed valve through the opening 11. It therefore will be manifest that a certain quantity of carbide will be separated from the remainder of the carbide within the reserve supply container and will be dumped through the opening 11 directly into the liquid within the tank 2 when the reserve supply feed or dump valve is swung from closed to open position and that the remainder of the supply of carbide that was in the reserve supply container will pass between the reserve supply feed valve and the end wall 12^b into the main carbide supply container. The quantity of carbide that was discharged through the opening 11 into the liquid within the tank 2 will be sufficient to cause upward movement of the bell 37 so that the quantity of carbide which passed from the reserve supply container into the main supply container will be fed from the latter as required by means of the usual automatic feed mechanism that is provided for that purpose. It therefore will be apparent that the operator of the generator will be apprised of the condition of the supply of carbide within the generator a considerable length of time before the available carbide within the generator is completely used up and in ample time to enable the operator to replenish the supply of carbide for operating the generator without any interruption of the service that the generator provides. 100

Obviously, our invention is susceptible of embodiment in forms other than that herein described and we therefore consider as our own all such modifications and adaptations of the form of the device herein described as fairly fall within the scope of the appended claims. 110

We claim:—

1. In an acetylene gas generator, a tank adapted to hold the liquid, a main carbide supply container having a main discharge opening at its lower end through which carbide may drop into the liquid in said tank and having a secondary discharge opening located above the level of the main discharge opening, automatic means for controlling the feeding of carbide from said main supply container through said main discharge opening, a reserve carbide supply container, and pivoted means for retaining carbide in said reserve supply container and operable to permit passage of a portion of the contents of said reserve supply container 120 125 130

through said secondary discharge opening into said tank and the remainder of the contents of the reserve supply container into said main supply container.

5. 2. In an acetylene gas generator, a main carbide supply container having a sloping bottom wall provided with a discharge opening at its lower end, said sloping wall having a secondary discharge opening at a higher level than said first named discharge opening, pivoted means for controlling discharge of powdered or granular material from said main supply container through said first named discharge opening, a reserve supply container comprising a hollow body secured within the main supply container in position to obstruct said second named discharge opening, said reserve supply container being open at its lower end, a valve normally preventing passage of granular or powdered material from the reserve supply container through the open lower end of the latter, said valve being operable to discharge a portion of the contents of the reserve supply container through said second named discharge opening of the main supply container and the remainder of the contents of the reserve supply container into said main supply container.
- 30 3. A reserve supply container for powdered or granular carbide comprising a vertically disposed hollow body having parallel side walls and parallel end walls, an obstruction extending from one of said end walls intermediate the height of the body toward the other end wall and terminating short of said last named end wall of the body, said obstruction having a width equal to the distance between the side walls of the body, a valve consisting of a plate disposed flatwise within the body of the container below the level of said obstruction, means supporting said plate within the body of said container to rock about an axis extending transversely of said plate intermediate the length of the latter, said valve plate being movable from position to close said body below the level of the obstruction to position to permit passage of carbide past said obstruction and past said plate through the open lower end of said body.

- 45 4. A container for powdered or granular carbide, said container comprising a hollow body having parallel vertical side walls and parallel vertical end walls, a horizontal rock shaft journaled in alined openings in the lower portions of said side walls, a valve plate secured intermediate its length on said rock shaft, said valve plate being adapted to close the space within said body when said rock shaft has been rocked to one position, an inclined deflector plate secured to an end wall of said body within said container, said inclined deflector plate having a width equal to the distance between the

side walls of said body, being disposed above said valve plate, and terminating at its free end short of the second end wall of the body, and means for operating said rock shaft.

5. A container for powdered or granular carbide, said container comprising a hollow body having parallel vertical side walls and parallel vertical end walls, a horizontal rock shaft journaled in alined openings in the lower portions of said side walls, a valve plate secured intermediate its length on said rock shaft, said valve plate being adapted to close the space within said body when said rock shaft has been rocked to one position, an inclined deflector plate secured to an end wall of said body within said container, said inclined deflector plate having a width equal to the distance between the side walls of said body, being disposed above said valve plate, and terminating at its free end short of the second end wall of the body, and means for operating said rock shaft, said valve being adapted to contact at one end with the lower end of said inclined deflector plate when said rock shaft has been rocked in one direction from said certain position thereof.

6. A reserve hopper for carbide comprising a hollow body open at its upper and lower ends, a vertically swingable dump valve pivoted intermediate its ends within the lower portion of said body and adapted when closed to prevent the passage of powdered or granular material from the body through the open lower end of the latter, means for operating said dump valve, and a deflector plate extending transversely within said body above one end portion of the valve and in position to be engaged by the other end of said valve when the valve is swung from closed position to open position, whereby a definite part of the contents of said container body will be separated from the remainder of the contents of the container body and will be dumped separately through the open lower end of said container.

7. In an acetylene gas generator, an outer shell having the lower portion thereof adapted for the reception of a liquid, a main carbide supply container positioned within said shell above said liquid, said main supply container having a hopper at its lower end and having a normally closed filler opening in its top, said hopper having a secondary discharge opening adjacent to its upper end, a reserve supply container comprising a vertically disposed hollow body open at its upper and lower ends, said reserve supply container being supported within said main supply container with the open upper end thereof underneath said filler opening, and with the open lower end thereof surrounding said secondary discharge opening of said hopper, a pivoted dump

valve in the lower part of said reserve supply container operable to dump a portion of the contents of the reserve supply container through said secondary discharge opening and to permit the remainder of the contents of said reserve supply container to move by gravity into said main supply container.

8. In an acetylene gas generator, an outer shell having the lower portion thereof adapted for the reception of a liquid, a main carbide supply container positioned within said shell above said liquid, said main supply container having a hopper at its lower end and having a normally closed filler opening in its top, said hopper having a secondary discharge opening adjacent to its upper end, a reserve supply container comprising a vertically disposed hollow body open at its upper and lower ends, said reserve supply container being supported within said main supply container with the open upper end thereof underneath said filler opening, and with the open lower end thereof surrounding said secondary discharge opening of said hopper, a pivoted dump valve in the lower part of said reserve supply container operable to dump a portion of the contents of the reserve supply container through said secondary discharge opening and to permit the remainder of the contents of said reserve supply container to move by gravity into said

main supply container, a dump valve operating mechanism including a lifter arm extending through an opening in the top of 35 said main supply container and having a laterally extending upper end portion, and a vertically movable elongated motion transmitting element operable at the upper end of said shell to lift said lifter arm upward 40 to open said dump valve.

9. In an acetylene gas generator, a tank adapted to hold the liquid, a main carbide supply container having a main discharge opening at its lower end through which carbide may drop into the liquid in said tank, and having a secondary discharge opening located above the level of the main discharge opening, automatic means for controlling the feeding of carbide from said main supply container through said main discharge opening, a reserve carbide supply container and pivoted means for retaining carbide in said reserve supply container and operable to permit passage of a 50 portion of the contents of said reserve supply container through said secondary discharge opening into said tank and the remainder of the contents of the reserve supply container into said main supply container. 55 60
